UNITED STATES PATENT OFFICE.

EDWARD G. BRADBURY, OF COLUMBUS, OHIO.

GAME.

1,381,164.

Specification of Letters Patent. Patented June 14, 1921.

Application filed August 3, 1920. Serial No. 400,962.

To all whom it may concern:

Be it known that I, EDWARD G. BRADBURY, a citizen of the United States, residing at Columbus, in the county of Franklin and State of Ohio, have invented certain new and useful Improvements in Games, of which the following is a specification.

The present invention consists in the provision of an improved game apparatus, which is in the nature of a hand manipulated receptacle, in which spaced ridges are provided and so distributed that counter members within the receptacle may be moved about therein, either by sliding movements or by being shaken or jostled, whereby through dexterous and skilled movements on the part of the operator said counter members will be caused to be moved within the receptacle so that the members will occupy a space defined by the ridges, whereby a certain distribution of the counter members in a prescribed order within said space will result in the termination of the game or puzzle played through the medium of the apparatus.

The object of the invention resides in the provision of a game apparatus of this character which will be of a small compact nature capable of being readily manipulated by being placed in the operator's hand so that the same may be readily tilted or moved from side to side to effect the movement of the internal counter members, whereby the latter will be caused to overcome the obstacles furnished by the inclusion of the ridges and passed through spaces defined between the ridges in order that the counter members may be positioned in a certain order within the interior of the apparatus and the confines of the ridges, the spaces between said ridges being of very sufficient size to permit the counter members to be passed therethrough, a feature which necessitates skill and patience on the part of the operator in causing the counter members to travel from the outer margins of the game to the inner counting portions thereof.

A further object of the invention resides in a game which will be simple in construction, inexpensive to manufacture and capable of furnishing considerable amusement and study to those operating the same.

For a further understanding of the invention, reference is to be had to the following description and to the accompanying drawing, in which similar characters of ref-

erence denote like and corresponding parts throughout the several views thereof:

Figure 1 is a plan view of my improved game apparatus, and,

Fig. 2 is a vertical transverse sectional view taken along the line 2-2 of Fig. 1.

As shown in the accompanying drawing my improved game apparatus comprises a box or receptacle 1, which is formed preferably from stamped thin sheet metal and comprises a bottom 2 and upstanding side walls 3, the upper edges of the latter being terminated in lateral flanges 4 upon which are seated the outer margins of a top 5, the latter being in the form of a transparent panel, and is secured in place by means of a fabric binding member 6, which is connected with the edges of the panel 5 and the adjacent edges of the walls 3 by means of a suitable adhesive.

The present invention consists essentially in stamping or otherwise forming spaced longitudinally and transversely extending ridges 7 in the bottom 2 of the receptacle. These ridges, as will be observed upon reference to Fig. 1, are spaced a predetermined distance from the side walls 3 so that an outer counter receiving space 8 will be provided around the margins of the bottom 2. Adapted to be situated within this space are a plurality of counter members 9, which in the present instance are in the form of dice and are therefore of cubical construction having numeral bearing faces. It will be observed that the members 9 are of such size as to be snugly received between the ridges 7 and the walls 3, a feature which normally serves to maintain the counter members within the spaces 8.

Normally, it is the object of the game to cause these counter members 9 to pass from the spaces 8 to an inner space 10 provided within the confines of the ridges 7, and to arrange the counter members within said space 10 in a manner presenting a certain prescribed or predetermined array of numerals. For instance, it may be the object of the game to position the counter members within the space 10 so that the faces thereof designating the numeral 6 will be presented to view upon gazing through the panel 5. Ordinarily, when a set of the games are provided the player first positioning the counter members in proper order is declared the winner. To manipulate the receptacle so that the counter members will be properly

positioned within the space 10 is a matter of considerable skill and patience on the part of the operator, since the counter members must be rolled in order to bring the proper 5 faces thereof into view, and this rolling or shaking of the game must be accomplished in such manner that the counter members already properly positioned will not be disturbed. Also, the game may be played by 10 but one person in the manner of executing a puzzle.

The counter members may reach the inner space 10 by tilting the same, after the fashion shown by dotted lines in Fig. 2, over the 15 shallow ridges 7, or the same may be moved until they are brought into registration with the gaps 11 provided between the ends of the ridges 7. These gaps are of sufficient width to permit the counter members, by careful 20 manipulation, to slip or pass therethrough. To start the game the receptacle is shaken sharply so that the counter members will assume various positions, or in other words will present surfaces of varying value. The 25 player who then forces the counter members into the space 10 in a prescribed order in the shortest length of time is the winner of the game. By tilting the counter members over the ridges 7 different counting faces will be 30 exposed to view and it is by this method mainly that the proper surfaces thereof are brought to view through the top 5 when said members are positioned within the central space 10. If the proper counting face has 35 been already exposed to view, when the counter members are positioned within the outer spaces 8, the best course would be to manipulate the box without changing the positions of the counter member in order that 40 the latter may be placed through one of the gaps 11, without tilting or rolling. It will be appreciated that the gaps 11 are of restricted width, or in other words a width barely exceeding that of the counter member 45 6 and hence the operator is required to carefully manipulate the box in order that a counter member may pass through said gaps without losing its counting position.

What is claimed is:

1. In a game apparatus of the class described, a relatively shallow receptacle including a transparent top, longitudinally and transversely extending ribs provided in the bottom of said receptacle and protruding into the latter, said ribs serving to divide the 55 bottom of the box into inner and outer spaces, counter members of cubical form arranged to be transferred from one of said spaces to the other against the opposition furnished by said ridges, and said ridges 60 being spaced from the transparent top of said receptacle a sufficient distance to allow the counter member to pass transversely over the same.

2. In a game apparatus of the class described, a box formed to include a bottom, upstanding side walls and a transparent top, shallow ridges provided in the bottom of said box, said ridges being spaced in the side walls of said box to define and divide inner 70 and outer spaces, counter members arranged to be transferred from one of said spaces to the other against the opposition furnished by said ridges, said ridges being spaced from said top a suitable distance to permit the 75 counter members to pass transversely over the same in passing from one of said spaces to the other, and said ridges having their ends spaced relatively a sufficient distance 80 to provide gaps through which said counter members are permitted to pass.

3. In a game apparatus of the class described, a relatively shallow receptacle, ribs provided in the bottom of said receptacle, said ribs serving to divide the receptacle 85 into inner and outer spaces, counter members of cubical form arranged to be transferred from one of said spaces to the other against the operation furnished by said ridges, and said counter members being capable of passing through gaps formed between adjacent 90 ends of said ridges.

In testimony whereof I affix my signature.

EDWARD G. BRADBURY.
